J. Ethiel Town 8743X

Letters Patent.

Whereas I have before referred to in these Letters Patent and
nowhere else, to my name, containing a description in
and of the said Ethiel Town, himself of his im-
provement in bridge patented the 28th day of ~~May~~
~~1831~~

Know that I, Ethiel Town, of the city of New York,
State of New York, and State of New York, have made an
improvement on my bridge patented on the 28th day of
May 1831, which is described as follows; reference
being had to the former description, deposited in the Patent
Office, the improvement on my former bridge which I now
wish to secured by Letters Patent, is as follows.

The side tress as described in my former patent, being com-
posed or formed with diagonal braces at any suitable
distance apart and one or more horizontal string-pieces
at top and bottom, on each side of the braces, and all
properly dimensioned; proportioned to a suitable height of
tress, and secured. What I claim as the improvement is
the addition of another similar set or series of bracing of
similar kind and dimensions, to be placed in a similar
manner, either directly opposite to the former, or in any
other manner so as to bring the second tier not opposite
to the former; but so that all the intersections of the
tress of the latter series shall fall between those of
the former tress, and the horizontal string-pieces, upon
which another tier of tress is to be formed similar to the
former, and upon the former, with one or more other series
of intermediate string-pieces, as required, for the

8743X

various shores, to be placed upon the extension of the last series of braces, arranged to appear as the following pieces; all of which last will be joints of the second series of braces, with the long pieces much as those of to be secured with one or more tenons, or other suitable fastenings, making in one way, two sets of four series each, of braces, and three series of three of four piping over one or more of the intersections of the joints of the traces to any number and extent appropriate in case of very wide spans or openings, so as to that and fourth, the sets or series of braces may be removed and added with their necessary long pieces, the ends of other fastenings, &c. to any number or extent required, one two or more of these traces with the long pieces, and in necessary parts as usual will answer all purposes in progress.
